UNITED STATES PATENT OFFICE.

BENJAMIN DAVIES, OF WEST HOBOKEN, NEW JERSEY, ASSIGNOR TO
I. STRAUS & SONS, OF NEW YORK, N. Y.

DESIGN FOR A GLASS VESSEL.

SPECIFICATION forming part of Design No. 24,355, dated June 4, 1895.

Application filed March 20, 1895. Serial No. 542,547. Term of patent 7 years.

To all whom it may concern:

Be it known that I, BENJAMIN DAVIES, a subject of the Queen of Great Britain, and a resident of West Hoboken, in the county of Hudson and State of New Jersey, United States of America, have invented and produced a new and original Design for Glass Vessels, of which the following is a specification, reference being had to the accompanying drawings, in which—

Figure 1 is a plan view of a dish ornamented with my design, and Fig. 2 represents a cross-sectional view of the same.

The leading feature of my design consists of an eight-pointed star composed of grooves which, at their centers are curved, the convex sides of the grooves being toward the center of the star.

In the design as represented in the accompanying drawings, an eight-pointed star is formed by the eight deep grooves *a* which meet at the margin of the dish and are curved from end to end, the greatest amount of curvature being in the middle portions of the grooves, and the convexity thereof being toward the center of the dish. In the tri-angular spaces formed in four of the points of the star, are fields *b* of fine crossed grooves, and in the other four spaces in the points of the star, are fields *c* composed of squares formed by grooves of medium depth, which

squares are, in turn, crossed by fine grooves. The fields *b* and *c* alternate in the points of the star around the sides of the dish, and in the spaces between the points of the star, are 35 the conventional fan-shaped figures *d*. The bottom of the dish, or the central space inside the star, is occupied by a figure *e* composed of twelve straight grooves, eight of which form an eight-pointed star while the other four diametrically connect the points of said star. Small fan figures occupy the spaces between the points of this star also.

In the accompanying drawings, the grooves forming the ornamentation of some of the 45 fields and spaces are omitted, in order to more prominently illustrate the leading feature of the design; but it is to be understood that the fields and spaces unoccupied in the drawings will, in practice, be ornamented by figures 50 duplicates of those shown.

Having thus described and illustrated my invention, what I claim is—

The design for glass vessels substantially as herein shown and described.

In testimony whereof I affix my signature in presence of two subscribing witnesses.

BENJAMIN DAVIES.
